UNITED STATES PATENT OFFICE.

DANIEL J. MURNANE, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

STORE-FRONT-CONSTRUCTION CORNER BAR.

Application filed December 2, 1921. Serial No. 519,408.

To all whom it may concern:

Be it known that I, DANIEL J. MURNANE, a citizen of the United States, residing at Chicago Heights, in the county of Cook and State of Illinois, have invented a new and useful Improvement in Store-Front-Construction Corner Bars, of which the following is a specification.

My invention relates to the corner-bars of store-front-construction at which the panes of glass of the store-front are securely held in angular position to each other; my primary object being to provide a construction of corner-bar, the member of which, located at the interior of the window structure, shall be adapted to permit of the positioning of the adjacent panes of glass at any desired angle relative to each other, thereby avoiding the necessity of employing different forms of inner members for constructions wherein the panes of glass extend at different angles relative to each other; other objects are to reduce the expense of corner-bar structures, render them more simple of construction, permit of their ready installation and perform in a highly efficient and satisfactory manner, the functions for which they are provided.

Referring to the accompanying drawing: Figure 1 is a plan sectional view, taken through the corner portion of a store-front construction, said construction involving a corner-bar constructed in accordance with my invention, the section being taken at the line 1—1 on Fig. 2 and viewed in the direction of the arrows. Figure 2 is a vertical section taken at the line 2—2 on Fig. 1 and viewed in the direction of the arrow; and Figure 3, a perspective view of one of the sections of the outer member of the corner-bar.

In the particular construction illustrated, the corner bar is formed of an inner member represented generally at 4, an outer member represented at 5, between which the panes of glass represented at 6 and 7 are to be clamped, and means represented generally at 8 for effecting the clamping of the panes 6 and 7 between the members 4 and 5, the corner-bar construction shown being intended primarily for use in an upwardly-extending position, as is well understood in the art. The inner corner-bar member 4 is shown

as of general U-shape, the body portion 9 being formed preferably of relatively heavy-gage steel the entire outer surface of which is sheathed as represented at 10, preferably with copper. The portions of the member 4 at which the panes of glass 6 and 7 bear, are represented at 11, these portions being so formed that the panes 6 and 7 may be set, and clamped to the member 4, at different angular positions relative to each other, as may be desired in the constructing of the store-front. The panes 6 and 7 are shown as extending at right angles to each other but, as is well understood in the art, it is often desirable to set these panes at different angles relative to each other and the accomplishment of this, by the use of a standard bar 8, is one of the purposes of my invention as above pointed out. The surfaces of the portions 11 which are contacted by the panes, are preferably of curved shape in cross-section as represented in Fig. 1, whereby bearing contact between the members 4 and the panes 6 and 7 is presented regardless of the angular positions of the panes. The inner edge portion 12 of the member 4 is shown as inwardly offset as represented at 13, this inset portion, if desired, extending the full length of the member 4 and being provided for a purpose hereinafter described. The member 4 is also provided with means, represented generally at 14, for cooperation with the devices, hereinafter described, and operating to effect the clamping of the panes 6 and 7 between the members 4 and 5, for maintaining the members 4 and 5 in position against rolling relative to each other.

The outer member 5 is shown of general angular shape in cross-section, this member in the particular illustrated embodiment of the invention comprising a sheet metal section extending parallel with the member 4 and of the length as commonly provided in structures of this character, this member being formed with seating surfaces 16, at which it is adapted to seat against the outer surface of the panes 6 and 7, these seating surfaces being shown as formed by the inwardly-turned portions 17 of the metal forming the bar-section 15. The member 5 as shown is also formed of a vertical series of plate-like sections 18, of the general sec-

tional channel shape shown in the drawings, each presenting a relatively flat portion 19 intermediate its lateral portions 20, these sections being arranged one above the other 5 in spaced relation within the angle of the section 15, the flat portions 19 of the sections 18 extending in a position directly opposite the deepest portion of the angle of the member 15 as shown in Fig. 1. The 10 sections 18 are preferably corrugated and flanged, as represented at 21 and 22 respectively in Fig. 3, to render them relatively stiff and adapt them to effectually resist stresses, tending to deflect them, exerted 15 against them by the devices hereinafter referred to and engaged thereby for firmly clamping the panes 6 and 7 between the members 4 and 5.

The means 8 are shown as of the screw-bolt type, it being preferred that a number 20 of these screw-bolts be provided in a vertical series, these screw-bolts extending through the portions 19 of the member 5 and the portions 13 of the member 4. One 25 of these similar screw-bolts is represented at 23, its head portion, represented at 24, being located at the outer surface of the portion 19 of the section 18, a nut 25 being screwed upon the threaded end of the bolt and 30 against the rear side of the portion 19. The extremity of the bolt 23, opposite its headed portion, has screwed thereon a combined nut and shouldered bushing 26 which extends into the channel provided by the deflected portion 13 at the rear side of the bar section 4 and also into the opening represented at 27 through which the bolt 23 extends, the shouldered portion 28 of this bushing overlapping the bottom wall of said groove, it 35 being understood that upon tightening the nut 26 the sections 4 and 5 will be drawn toward each other with the result of firmly 40 clamping the panes 6 and 7 between the rounded surfaces of the portions 11 of the member 4, and the portions 17 of the member 5.

The means 14 hereinbefore referred to, by preference and as shown, are in the form of separate plates 29 located in the space between 50 the portions 11 of the member 4 and arranged in spaced relation in an upright series, these plates being preferably made of sheet metal and bent to present at their opposite edges at which they oppose the free edges of the parts 11, the grooved flanges 55 30 at which grooves they nest with the free edges of the portions 11 as shown, these plates containing vertically elongated slots 31 therein through which the screw devices 60 23 extend.

It will be understood from the foregoing that the means 14, which may, if desired, be a continuous strip instead of formed in sections as stated, serves to prevent the rolling or rocking of the member 4 relating to the

member 5 and the pane 6, and 7, in the drawing of the members 4 and 5 together with clamping contact with the panes, these means in effect producing a centralizing of the two members 4 and 5 relative to each other and insuring the assembly of the parts of the store-front-corner construction in the desired position and causing the structure to present the desired strength and rigidity.

The slots 31 are preferably formed by 75 punching them in the plates and deflecting the metal, forming the walls of the slots, as shown at 31^a in Fig. 1, to provide smooth extended bearing-surfaces for the bolts 23 extending therethrough and which closely 80 fit between opposed walls of these slots.

It will furthermore be noted that by constructing a corner-bar in accordance with my invention the need of providing, between the inner surfaces of the panes 6 and 7 and the inner member of the corner-bar, a separate sheet metal member, as is common practice, is avoided by reason of the construction of the member 4 as shown and the sheathing thereof with a material, copper 90 being preferred as hereinbefore stated, which may contact with the glass without danger of injury to the latter.

It will also be understood that the provision of the member 4, as described, adapts it 95 for use where the panes 6 and 7 are to extend at different angles relative to each other therefore avoiding the necessity of providing a large number of different forms of inner corner-bar members for use where 100 the angles at which the panes are set, differ. When the form of outer member 5, as shown, is used, different forms of these members in which the angle at which the portions 17 extend relative to each other, 105 would be provided to correspond with the angular relation of the panes to each other.

While I have illustrated and described a particular construction embodying my invention, I do not wish to be understood as 110 intending to limit it thereto as the same may be variously modified and altered without departing from the spirit of my invention.

What I claim as new, and desire to secure by Letters Patent, is:

1. A store-front-construction corner-bar comprising a body member formed with spaced-apart portions forming a part of said body and affording seating surfaces for the panes of glass to be secured in position in different angular positions of said panes, an apertured member extending into the space between said portions and opposing the latter, substantially in line with said surfaces, a member to extend adjacent the surfaces of said panes opposite those engaging said seating surfaces, and means for effecting the clamping of said panes between said body member and said last-named member, said means engaging all of said members and 125 130

operating to prevent turning of said body member and said last-named member relative to each other.

2. A store-front-construction corner-bar comprising a body member of substantially U-shape in cross section with its edge portions deflected to form curved seating surfaces for the panes of glass to be secured in position in different angular positions of said panes, and an apertured member extending into the space between said portions and opposing the latter substantially in line with said seating surfaces, a member to extend adjacent the surfaces of said panes opposite those engaging said seating surfaces, and means for effecting the clamping of said panes between said body member and said last-named member, said means engaging all of said members and operating to prevent turning of said body member and said last-named member relative to each other.

3. A store-front-construction corner-bar comprising a body member of substantially U-shape in cross-section with its edge portions inwardly turned and forming curved seating surfaces for the panes of glass to be secured in position in different angular positions of said panes, and an apertured member extending into the space between said

portions with its ends recessed to receive 30 said inturned edge portions of said body member, a member to extend adjacent the surfaces of said panes opposite those engaging said seating surfaces, and means for effecting the clamping of said panes between 35 said body member and said last-named member, said means engaging all of said members and operating to prevent turning of said body member and said last-named member relative to each other.

4. A store-front-construction corner-bar comprising a member presenting surfaces spaced apart to form seating surfaces for the panes of glass to be secured in position in different angular positions of said panes, 45 said member being located within the angle formed by the panes, a member to extend adjacent the surfaces of said panes opposite those engaging said seating surfaces, a third member located between the portions presenting said surfaces and holding them in spaced relation, and means for effecting the clamping of said panes between said first and second named members and engaging all of said members and operating to prevent 50 turning of said first and second named members relative to each other.

DANIEL J. MURNANE.
